UNITED STATES PATENT OFFICE.

ERNEST ROTH, OF PERU, ILLINOIS.

DESIGN FOR A CLOCK-CASE.

SPECIFICATION forming part of Design No. 24,736, dated October 8, 1895.

Application filed August 7, 1895. Serial No. 558,561. Term of patent 7 years.

To all whom it may concern:

Be it known that I, ERNEST ROTH, a citizen of the United States, residing at Peru, in the county of La Salle and State of Illinois, have 5 invented a new and original Design for Clocks, of which the following is a specification.

My invention relates to a new design for clock-cases and is illustrated in the accompanying drawing, wherein I have shown a single perspective view of the clock-case. The body A of the clock-case is rectangular in shape and the sides and front are made of one piece of material. The front of the case is smooth and continuous, as shown, except for 10 the opening through which the clock-dial B is seen. The case is enlarged at the bottom,

so as to form the base C. This base is provided with grooves or indentations, as shown.

The essential features of my design consist of the rectangular case A, having a smooth 20 face, said face being provided with an opening for the clock-dial, the case being enlarged at the bottom, so as to form the base C, as shown.

I claim—

25 The design for a clock-case as herein shown and described.

ERNEST ROTH.
